COMPARTMENT BOX

Ralph V. Burdick, Albany, N. Y.

Application July 12, 1934, Serial No. 734,827

1 Claim. (Cl. 220—20)

This invention relates generally to a metallic box, primarily intended to contain shoe polish and other polishing preparations, although it is susceptible for other uses, and its general use is contemplated by the claim.

The invention has for its primary object the provision of a compartment box of the class in question, wherein each compartment is tightly covered to preserve its contents, and wherein each compartment can be easily opened independently of any other compartment as the occasion may require.

In carrying out the invention I employ a plurality of box units designed to be snugly and tightly fitted one within the other a definite distance to form the various compartments, and a cover for the uppermost compartment, the component units being capable of independent separation from the adjacent unit, so that the various compartments can be selectively opened.

In accordance with the present invention the various units of the box are constructed for compact assemblage in a manner whereby a box of the class in question may be provided with any desired number of compartments, and at the same time provide a comparatively small box structure as a whole.

Another object of the invention resides in providing the upper edges of the various units of the box with outwardly extending curled flanges which not only strengthen the units, but are utilized to facilitate selective opening of the compartments of the box.

In the drawing forming part of this application like numerals of reference indicate similar parts in the several views and wherein:

Figure 1 is a view in elevation of one embodiment of the invention.

Figure 2 is a vertical sectional view through Figure 1.

Figure 3 is a view similar to Figure 1 of a modified construction.

Figure 4 is a vertical sectional view through Figure 3.

Figure 5 is a fragmentary plan view of the lowermost box unit embodied in the modified construction.

The various units embodied in the compartment box forming the subject matter of the present invention are made of sheet metal. While these units are shown as annular in contour, resembling generally the type of box in which shoe polish or the like is sold, these units may of course vary in size and design to provide a compartment box for any specific use. It is

also to be understood that while I have illustrated and hereinafter described a two compartment box, any number of units may be employed to provide a box with any desired number of compartments within the scope of the invention.

Referring to the drawing in detail, and more particularly Figures 1 and 2, 10 and 11 indicate a pair of box units, while the cover unit is indicated at 12. The box unit 10 is formed with a flange 13 projecting from its upper edge, the flange being curled inwardly to provide the unit with a smooth rounded edge to protect the fingers of the user from injury. The wall of the unit is also formed with an inwardly extending bead or rib 14 to limit the insertion of the box unit 11 within the unit 10. Obviously, the box unit 11 is of a size to be snugly and tightly fitted within the box unit 10, reposing upon the bead or rib 14 and thereby defining a double compartment box of the class in question. The wall of the box unit 11 is also formed with an outwardly extending flange 15 curled inwardly to provide a smooth rounded edge. Manifestly, when the box unit 11 is fitted within the box unit 10, the curled flanges 13 and 15 of said units are spaced a predetermined distance, to permit the insertion of a coin 18 or any other suitable instrument therebetween to effect a separation of said units with a minimum of effort, as the occasion may require.

The uppermost unit of the box is tightly closed by a suitable cover unit 12 which may be of any suitable construction, capable of being easily removed. However, I preferably employ a friction cover of a size to be tightly fitted within the adjacent box unit a predetermined distance. By virtue of the cross-sectional contour of the cover unit herein illustrated, the friction wall of the cover effectively engages the wall of the box unit 11. The cover unit is also formed with an outwardly extending flange 16 curled inwardly to provide a smooth rounded edge, and this flange 16 is spaced a definite distance from the flange 15 of the adjacent box unit, to permit the insertion of a coin or other suitable instrument therebetween to facilitate removal of the cover. The wall of the cover unit is also formed with a shoulder 17 adapted to engage the upper edge of the box unit 11 and thereby limit the insertion of the cover within the box unit.

In Figures 3 and 4 I have illustrated a modified form of the invention, wherein the box units are indicated at 10' and 11', while the cover unit is indicated at 12'. The upper edges of the box unit are formed with outwardly extending curled

flanges indicated at 13' and 15' respectively, these units being identical in construction with the box units hereinabove described, except the box unit 10' has a straight interrupted wall to 5 permit the box unit 11' to be wholly fitted within the lowermost box unit 10'. Consequently the flanges 13' and 15' of the respective box units are permitted to be brought together in contacting engagement, or substantially so, as illustrated. The cover unit 12' is identical in construction with the cover unit above described, being formed with an outwardly extending curled flange 16' and a shoulder 17' adapted to engage the adjacent edge of the box unit 11' to limit 15 the insertion of the cover unit therein, and space the flange 16' a definite distance from the flange 15' of the adjacent box unit. This construction permits the insertion of a coin or other suitable instrument between said flanges to effect a removal of the cover unit when desired.

The lowermost box unit 10' has pivoted on the wall thereof a lever 19 of any suitable construction or design, the upper end of which is utilized to engage the flange 15' of the box unit 11' to 25 effect a separation of said units as the occasion may require. Obviously the lever 19 operates through a cut away portion 20 of the flange 13' of the lower box unit for the purpose just stated. The normal position of the lever is clearly illustrated in Figure 3, and when the lever is depressed the upper end thereof passes through the cut away portion 20 of the flange 13', and engages the flange 15' of the box unit 11' to effect a separation of said units. By virtue of the construction illustrated and described, it is clear that any one of the component units of the box can be separated from its adjacent unit, so that access may be had to any compartment independently of the other compartment, and this may be 35 accomplished by the use of a coin or other suitable instrument in the manner above stated, or by the use of a coin and lever 19. If more than two compartments are provided for, by the use

of a multiplicity of units, only one lever will be employed to effect a separation of the two lowermost units, the remaining units being separated by the use of a coin or the like.

While it is believed that the nature and advantages of the invention will be readily understood, I desire to have it known that I do not limit myself to what is herein illustrated or described, and that such changes in the construction may be resorted to as fall within the scope 10 of what is claimed.

What is claimed is:

A shoe polish box having superimposed compartments, and including a body unit having an annular bead projecting inwardly from the wall 15 thereof a definite distance from its upper edge, and a flange projecting outwardly from said edge, an intermediate removable box-like unit partly and frictionally fitted within the body unit and reposing on said rib to define a lower compartment between the bottoms of said units, a flange projecting outwardly from the upper edge 20 of the intermediate unit and spaced from the flange of the body unit whereby said units may be readily separated, and a removable friction cover unit including an annular side wall partly 25 and frictionally fitted in said intermediate unit and having a convex top wall curved upwardly from the lower edge of its side wall and lying in a plane substantially flush with the upper edge 30 of said cover unit, the side wall of said cover unit having an outwardly projecting annular shoulder reposing on the upper edge of the intermediate unit to limit the insertion of the cover unit and thereby define a compartment 35 between these adjacent units and a flange projecting from the upper edge of the cover unit and spaced from the flange of the intermediate unit, whereby any of said units can be selectively separated from the adjacent unit to permit access to any particular compartment.

RALPH V. BURDICK.
